UNITED STATES PATENT OFFICE.

RAYMOND R. KIRSCH, OF ST. LOUIS, MISSOURI.

METALLIC HEEL.

1,425,866.

Specification of Letters Patent. Patented Aug. 15, 1922.

Application filed March 24, 1921. Serial No. 455,355.

To all whom it may concern:

Be it known that I, RAYMOND R. KIRSCH, a citizen of the United States, residing at the city of St. Louis and State of Missouri, 5 have invented a new and useful Metallic Heel, of which the following is a specification.

This invention relates to improvements in metallic heels, and consists in the novel construction hereinafter disclosed.

An object of the invention is to provide a metal heel including an improved means for connecting the heel with the shoe.

Another object of the invention is to provide in a metallic heel an attaching plate adapted to be secured directly to the shoe, with provision whereby the plate may be coupled with the metallic heel for holding the same in place on the shoe.

20 Additional advantages of the construction will be apparent from the following detail description thereof, taken in connection with the accompanying drawing, in which—

Fig. 1 is a plan view of the heel body with 25 the retaining plate removed.

Fig. 2 is a vertical section through a portion of the shoe showing the construction of the attaching means of the present invention.

30 Fig. 3 is a transverse vertical section taken substantially on the line 3—3 of Fig. 2.

Fig. 4 is a top plan view of the retaining plate removed.

Fig. 5 is an edge view of the same element.

In the embodiment of the invention illustrated in the drawing, the metallic heel body is formed from a hollow casting leaving an open top 1 around the inner edge of which 40 is formed a series of suitably spaced inwardly extending lugs 2. The upper face of the lugs 2 is slightly below the upper edge of the wall of the hollow body. The inner face of these lugs is stepped, as clearly 45 shown in Figs. 2 and 3, forming a shoulder 3. The edge of each of the lugs is undercut along the line of the upper face of the shoulder 3 forming recesses 4. A metallic plate 5, conforming in outer contour to the 50 curve of the heel section of the shoe and being composed preferably of a light spring steel, is provided. This plate constitutes a retaining plate and is designed for direct attachment with the bottom surface of the heel portion of the shoe by being nailed thereto, 55 the nails extending through a series of per-

forations 6 in the plate, said perforations being disposed at suitable intervals through the plate.

Around the marginal edge of the plate 5 60 are a series of down-pressed tongues 7 cut out of and depressed from the surface of the plate. These tongues register with the lugs formed in the hollow body.

It will be noted that in the original condition of the tongues they extend downwardly at an angle slightly less than a right angle to the under face of the plate, so that the tongues incline slightly toward the recesses 4, the extreme point of the tongues 70 being slightly out-turned. This retaining plate 5 is first attached to the heel portion of the shoe in the manner described. The heel body is brought into registration with the plate, so that after the retaining plate 75 has been forced into place, the plate will fit within the upper edge of the heel body, and the under face of the plate will rest upon the upper face of the lugs 2.

By exerting pressure over the several 80 tongues on the retaining plate by a suitable presser element from within the shoe and against the bottom thereof, the tongues are forced into the respective recesses 4, the ends of the tongues up-turning as clearly shown 85 in Figs. 2 and 3, and riveting into the upper wall of said recesses 4.

The construction provides convenient means for rigidly attaching the metallic heel body to the shoe. The attachment 90 may be effected with great facility. The construction also provides a means of attachment or connection between the heel body and the shoe which is neat in appearance, as the upper edge of the heel body 95 will lie in very close proximity to the surface of the heel portion of the shoe, the attaching means being entirely concealed by the upper edge of the metallic heel body.

I am aware that the invention may be 100 modified in certain particulars without departing from the spirit and scope thereof. I do not restrict myself, therefore, to unessential features, but what I claim and desire to secure by Letters Patent, is:—

105 1. In a metallic heel the combination with a hollow metallic heel body having recesses in the upper portion thereof opening inwardly, and shoulders extending inwardly below said recesses, of a metallic retaining 110 plate adapted to be attached to the heel portion of the shoe, and tongues in connec-

tion with said heel plate adapted by pressing action against said shoulders to be bent into said recesses.

2. In a metallic heel the combination with 5 a heel body, of lugs extending around the interior of said heel body below the upper edge thereof, and having tongue receiving recesses therein, shoulders extending inwardly below said recesses, a metallic plate 10 adapted to be attached to the heel portion of the shoe, and tongues carried by said plate adapted by pressing action against said shoulders to be bent into the recesses in said lugs.

15 3. In a metallic heel the combination with a hollow metallic heel body, of lugs extending around the interior of said heel body below the upper edge thereof, and having tongue receiving recesses therein, shoulders 20 extending inwardly below said recesses, a metallic retaining plate adapted to be attached to the heel portion of the shoe, and tongues carried by said plate adapted to contact with the inner ends of said lugs and 25 adapted by pressing action against said shoulders to be bent into the recesses in said lugs.

4. In a metallic heel, the combination of a hollow metallic heel body having an open-

ing in the top thereof, a series of lugs spaced 30 at intervals around the inner surface of the heel body below the top edge thereof, a metallic retaining plate adapted to be connected with the heel portion of a shoe, said retaining plate having downwardly deflect- 35 ed tongues and arranged to rest upon the upper surface of said lugs, the lugs being provided with recesses for receiving in holding engagement said tongues of the retaining plate.

5. In a metallic heel, the combination with a retaining plate having downwardly deflected tongues spaced at intervals around the marginal edge thereof, a metallic heel body having an opening in the top, a series 45 of spaced lugs around the inner surface and adjacent the upper edge of the wall of the heel body, said lugs having under-cut recesses in the inner face thereof, and a guiding shoulder below said recesses, whereby 50 when said heel body is pressed in contact with said retaining plate the tongues of the retaining plate will be guided into and be over-turned against the upper wall of the recesses, thereby effecting a holding engagement between the retaining plate and the heel body.

RAYMOND R. KIRSCH.
